FIG. 4 is a left side view of the cosmetic compact shown in FIG. 1;

FIG. 5 is a right side view of the cosmetic compact shown in FIG. 1;

FIG. 6 is a top view of the cosmetic compact shown in FIG. 1;

FIG. 7 is a bottom view of the cosmetic compact shown in FIG. 1;

FIG. 8 is a bottom perspective view of the cosmetic compact shown in FIG. 1;

FIG. 9 is a top perspective view of a second embodiment of a cosmetic compact in an opened position. The inside surface of the lid includes a mirror, which is represented with oblique lines;

FIG. 10 is a front view of the cosmetic compact shown in FIG. 9;

FIG. 11 is a back view of the cosmetic compact shown in FIG. 9;

FIG. 12 is a left side view of the cosmetic compact shown in FIG. 9;

FIG. 13 is a right side view of the cosmetic compact shown in FIG. 9;

FIG. 14 is a top view of the cosmetic compact shown in FIG. 9;

FIG. 15 is a bottom view of the cosmetic compact shown in FIG. 9;

FIG. 16 is a bottom perspective view of the cosmetic compact shown in FIG. 9.

FIG. 17 is a top perspective view of a third embodiment of a cosmetic compact in an opened position with a cosmetic pan and a cosmetic applicator each shown in dashed lines;

FIG. 18 is a front view of the cosmetic compact shown in FIG. 17;

FIG. 19 is a back view of the cosmetic compact shown in FIG. 17;

FIG. 20 is a left side view of the cosmetic compact shown in FIG. 17;

FIG. 21 is a right side view of the cosmetic compact shown in FIG. 17;

FIG. 22 is a top view of the cosmetic compact shown in FIG. 17;

FIG. 23 is a bottom view of the cosmetic compact shown in FIG. 17;

FIG. 24 is a bottom perspective view of the cosmetic compact shown in FIG. 17;

FIG. 25 is a top perspective view of a fourth embodiment of a cosmetic compact in an opened position;

FIG. 26 is a front view of the cosmetic compact shown in FIG. 25;

FIG. 27 is a back view of the cosmetic compact shown in FIG. 25;

FIG. 28 is a left side view of the cosmetic compact shown in FIG. 25;

FIG. 29 is a right side view of the cosmetic compact shown in FIG. 25;

FIG. 30 is a top view of the cosmetic compact shown in FIG. 25;

FIG. 31 is a bottom view of the cosmetic compact shown in FIG. 25; and,

FIG. 32 is a bottom perspective view of the cosmetic compact shown in FIG. 25.

The dashed lines in FIGS. 1, 6, 17 and 22 are included for the purpose of illustrating portions of the cosmetic compact that form no part of the claimed design.
